UNITED STATES PATENT OFFICE.

CHARLES A. BABCOCK, OF BUFFALO, NEW YORK, ASSIGNOR TO PRATT & LETCHWORTH, OF SAME PLACE.

DESIGN FOR A CARRIAGE-STEP.

SPECIFICATION forming part of Design No. 15,760, dated February 3, 1885.

Application filed December 31, 1884. Term of patent 7 years.

To all whom it may concern:

Be it known that I, CHARLES A. BABCOCK, a citizen of the United States, residing at Buffalo, in the county of Erie and State of New York, have invented and produced a new and original Design for Carriage-Steps, of which the following is a specification.

This design relates to the ornamentation of the upper surface of a carriage-step by means of ornamental ribs; and it consists of the special features, which will be hereinafter described and claimed, and which are represented in the accompanying drawing, which represents a top plan view of the carriage-step.

A represents the plate of the carriage-step, square or rectangular in form, and provided with a marginal bead, *a*.

B represents four intersecting rings arranged on the plate A, and provided with internal stars, C.

D represents four groups of parallel ribs extending from the four sides of the plate A inwardly to the rings B, and two arc-shaped ribs *d*. The ribs D of each group stand at right angles to the adjacent side of the plate A, and the four groups of ribs D are separated by diagonal ribs *e*.

I claim—

The design for a carriage step, consisting of rings B, provided with stars C, and ribs D, covering the portions of the plate outside of the rings B, substantially as shown and described.

Witness my hand this 19th day of November, 1884.

CHAS. A. BABCOCK.
